UNITED STATES PATENT OFFICE.

WILLIS G. YOUNG, OF CHICAGO, ILLINOIS.

DESIGN FOR A GAME-BOARD.

51,830.

Specification for Design.

Patented Feb. 26, 1918.

Application filed December 26, 1917. Serial No. 209,011. Term of patent 7 years.

To all whom it may concern:

Be it known that I, WILLIS G. YOUNG, a citizen of the United States, residing at Chicago, in the county of Cook and the State of Illinois, have invented a new, original, and ornamental Design for Game-Board, of which the following is a specification, reference being had to the accompanying drawing, forming part thereof.

The figure is a plan view of a game board showing my new design.

I claim:

The ornamental design for a game board as shown.

WILLIS G. YOUNG.

Witnesses:

OSCAR HOCHBERG,
HARRIET FAUSELOW.
